UNITED STATES PATENT OFFICE

2,414,191

ELECTRIC SWITCH

William B. Coon, Chicago, Ill., assignor to
 Simpson Electric Company, Chicago, Ill., a corporation of Illinois

Application June 2, 1945, Serial No. 597,240

11 Claims. (Cl. 200—6)

1

The present invention relates to electric switches and is particularly concerned with electric switches adapted to be used for effecting the switching necessary to connect in circuit the proper instruments, sockets, etc., in a tube tester.

One of the objects of the invention is the provision of an improved electric switch which is very compact, which occupies a minimum amount of space, and which is adapted to be manufactured at a very low cost.

Another object of the invention is the provision of improved electric switches of the class described which have a special type of actuating and indicating member which is adapted to project from a panel to permit the actuation of the switch and to indicate its position at all times.

Another object of the invention is the provision of an improved switch structure of the class described which has a quick make and quick break and which has a wiping action between the contacts of the switch so that the circuits are made and broken with a minimum amount of arcing and so that the contact resistance is reduced to a minimum.

Although the present switches are particularly adapted to be advantageous for certain uses mentioned above, I desire it to be understood that the switches are also of general application and may be used for many other purposes.

Another object of the invention is the provision of an improved electric switch of the class described having a snap action and means for holding the switch in any of its actuated positions but which is also adapted to be actuated in common with a plurality of similar switches by a single actuating device so that all of the switches may be simultaneously returned to their initial position.

Another object of the invention is the provision of an improved switch structure which is adapted to be embodied in double throw or multiple switches and which may include as many gangs as desired on a single elongated shaft.

Another object of the invention is the provision of an improved switch structure having an improved actuating member and improved indicia whereby the switch has a plurality of different positions but only one of the indicia corresponding to its present position is visible at any time.

Other objects and advantages of the invention will be apparent from the following description and the accompanying drawings, in which similar characters of reference indicate similar parts throughout the several views.

2

Referring to the drawings of which there are two sheets:

Figure 1 is a fragmentary sectional view of a panel equipped with a plurality of switches constructed according to the invention and adapted to be returned to initial position by a single actuator;

Fig. 2 is a fragmentary front elevational view of the panel with the switch structures shown in dotted lines;

Fig. 3 is a side elevational view of a switch unit embodying the invention with certain parts shown in section, taken on the plane of the line 3—3 of Fig. 8, looking in the direction of the arrows;

Fig. 4 is a full size side elevational view of the switch;

Fig. 5 is a similar view showing the switch including two banks of contacts;

Fig. 6 is a sectional view taken on the plane of the line 6—6 of Fig. 3 looking in the direction of the arrows;

Fig. 7 is a side elevational view of the switch of Fig. 3 shown on a scale corresponding to twice the size of the switch;

Fig. 8 is a similar side elevational view of the other side of the switch of Fig. 7;

Fig. 9 is an exploded view showing the various parts of the rotating contact member prior to their assembly;

Fig. 10 is a plan view of one of the contacts carried by their rotatable contact member;

Fig. 11 is a fragmentary sectional view of the switch taken on the plane of the line 11—11 of Fig. 8 looking in the direction of the arrows;

Fig. 12 is a fragmentary view in perspective showing the structure of one of the frame members; and

Fig. 13 is another fragmentary view in perspective showing the structure of the other of the frame members.

Referring to Figs. 3, 7 and 8, 20 indicates in its entirety one of the switch units embodying the invention, a plurality of which are shown in Fig. 1.

45 The switch unit 20 is provided with a supporting frame which may consist of a pair of frame members 21, 22 of metal. For example, frame member 21 consists of a strip of sheet metal having a flat body portion 23 which is provided at each 50 end with a laterally turned end flange 24 and an inwardly turned attaching flange 25 carried by the end flange 24.

The attaching flanges are located at right angles to the body portion 23 and are provided with 55 threaded bores 26 for receiving the screw bolts 27

(Fig. 1) by means of which the switch units are attached to a panel 28. The end flanges 24 are preferably formed with rectangular slots 29 in their edges, leaving a pair of outwardly projecting lugs 30 for engagement with the other frame member 22.

The frame member 22 may consist of a straight piece of sheet metal each end of which is formed with the inwardly extending rectangular slots 31 adjacent the end, of such a size as to receive the lugs 30 and the body portion 32 between the slots 31 is of sufficient width to be received in the slot 29 of the end flange 24. Thus, when these frame members 21 and 22 are assembled as shown in Fig. 3, the ends of the lugs 30 may be riveted over slightly to hold the frame in assembled relation.

The two frame members 21 and 22 are provided with a pair of aligned cylindrical bores 33, 34 for receiving the stub shaft 35 which carries the rotating actuating disc 36. The length of the stub shaft 35 depends upon the number of banks of contacts that are intended to be employed upon each unit. As shown in Fig. 4, the unit may have one bank of contacts, or, as shown in Fig. 5, two banks, or any suitable number of banks of contacts may be employed, depending on the number of contacts which it is desired to actuate simultaneously.

The actuating disc 36 preferably consists of a molded member made of a phenolic condensation compound which is molded about the shaft 35 and about anchoring formations carried by a metal disc 37 that is located in the right face of the actuating disc 36. Metal disc 37 may be secured in place by a screw bolt 38 as shown in Fig. 3 or it may have a plurality of anchoring members cut out of its periphery and bent inward to be anchored in the molded insulation of the actuating disc 36.

The metal plate 37 serves as a part of the snap mechanism and for retaining the switch in its actuated positions and this plate is provided with a central aperture 39 that registers with the aperture 40 in the actuating disc 36.

In addition to this, the metal disc 37 has a plurality of circular apertures 41-46 (Fig. 8) which are countersunk at their outer end so as to provide a better socket for a steel ball 47 which is located to be received in the apertures 41-46. The ball 47 is carried in a cylindrical bore 48 in the frame member 22, this bore being located at a suitable radius from the axis of shaft 35 so that the ball is adapted to be received in any of the sockets 41-46 carried by the rotatable actuating member 36. Ball 47 projects from its bore 48 in the frame member 22 to engage the metal plate 37 on the left, and on the right hand side in Fig. 3 the ball is engaged by a leaf spring 49 which urges it toward the rotatable actuating member 36.

The leaf spring 49 may be made of any suitable material such as spring brass or bronze, and it comprises an elongated strip of this sheet metal having an enlarged attaching flange 50 provided with apertures for receiving the rivets 51 passing through this flange and through the frame member 22 to secure the leaf spring 49 to frame member 22. The leaf spring extends longitudinally of the frame member 22 and thus has considerable length so that it need not be bent beyond its elastic limit. Its length is such that it projects above the end flange 24 of the switch unit, the upwardly projecting portion serving to be en-

gaged by a common actuator which will be further described in respect to Fig. 1.

Spring 49 urges the ball 47 toward the left but permits the ball to be cammed out of the sockets 41-46 when the rotatable member 36 is turned. The actuating disc 36 includes a circular body portion 52 in the form of a plate of molded insulation which is provided with a centrally located cylindrical hub 53 and a spring housing flange 54 extending in the same direction as the hub and located near the periphery of the disc 52. The edge 55 of the disc 52 may be rounded and is preferably knurled as shown for convenient engagement with the fingers which actuate the disc by frictional contact.

The cylindrical housing flange 54 may be provided on its cylindrical periphery with numerical indicia indicated at 56 (Fig. 4) showing the position of the switch at any time. The axial length of the hub 53 and housing flange 54 is such that rotatable actuating member 36 may be received between the frame members 21 and 22 where it is rotatably supported by the shaft 35 engaging in bores 33, 34.

25 The space between the hub 53 and housing flange 54 houses a spiral ribbon spring 57 which is used to urge the actuating member 36 toward its initial position. The frame member 21 carries a metal pin 58 (Fig. 3) riveted in a bore and projecting into a hook 59 which is formed by curling one end of the spring into partially cylindrical form. The other end of the spring has a cylindrical formation 60 which may be slid axially into a cylindrical bore 61 that is formed in the housing flange 54, thus anchoring this end of the spring to the actuating member 36. The strength of the spiral spring 57 is sufficient to rotate the member 36 and its rotatable switch members when the pressure of spring 49 is released, but as long as spring 49 presses the ball 47 into a socket 41-46, the spring 57 is not strong enough to alter the position of the rotatable member 36.

45 In addition to the sockets 41-46 for the ball 47, the plate 37 preferably has an arcuate slot 62 which is of sufficient length to determine the range of movement of the rotatable member 36. Slot 62 is located to be engaged by an inwardly projecting lug 63 which may form a part of frame member 22 (see Fig. 13), being bent inwardly from the frame member 22, to extend into the slot 62. The end 64 of slot 62 determines the limit of rotation in a clockwise direction of the rotatable switch and the end 65 of the slot 62 determines the limit of motion in a contrary direction.

55 In order to reduce the friction between the end of the insulating hub 53 and the adjacent frame member 21, a washer 66 is carried by the shaft 35. The left end of shaft 35 (Fig. 3) is provided with one or more non-circular portions 67 such as for example flat surfaces, and the shaft 35 is adapted to actuate a rotatable switch member 68 for each bank of contacts. In Fig. 5 this flattened portion of the shaft 35 has been extended far enough to support two such rotatable switch members 68 and 69.

70 The rotatable switch member 68 is shown with its parts in exploded form in Fig. 9 and this member preferably comprises a disc 70 of insulating material such as indurated fiber or a phenolic condensation molding compound. Disc 70 is provided with the centrally located non-circular aperture 71 which is complementary to the external shape of the shaft 35 at its flattened por-

75

tions 67. The disc 70 is preferably provided with a plurality of partially circular apertures 72 which are substantially rectangular in shape but are arranged along the line of a circle, these slots being adapted to receive the securing members that are carried by a pair of annular contact members 73, 74.

Each annular contact member comprises a flat sheet metal member in the form of an annulus and having a plurality, such as for example four, inwardly extending radial tabs 75 which are bent in an axial direction, the axial portion being called a securing tab 76 and being provided with an axially extending slot 77. The securing tabs 76 are wide enough and thick enough to fit in the slot 72 and they are properly located to register with four of these slots.

Thus, the annular contact plates 73 and 74 may be secured to the opposite sides of the insulating disc 70 by passing the securing tabs 76 through predetermined slots 72 and by spreading the axially extending slots 77. The annular contact members 73 and 74 are of such size that only the innermost portion of these annular members rests on the faces of the insulating disc 70 and thus the annular members 73 and 74 project beyond the edge 78 of the insulating disc 70. Since the tabs 76 may be located in spaced slots 72, the two annular members 73 and 74 may be insulated from each other and if desired each of these annular members might be used for a contact.

However, in the embodiment of Fig. 3 only the outermost annular member 73 has been used for a contact while the other annular member 74 merely serves as a guide for holding the rotatable switch member 68 upon the shaft 35. This is accomplished by means of the switch contact bank 79 (Fig. 7) which carries a multiplicity of fixed contacts 80-85. The contact bank 79 consists of a plate of insulating material such as a phenolic condensation compound which is arcuate in shape, the arcuate portion 86 being substantially concentric but spaced from the rotatable switch member 68.

At each end the arcuate portion 86 has an enlargement 87 provided with apertures for receiving the screw bolts 88 which pass through these apertures and are threaded into the frame member 21. An insulating spacer washer 89 is carried by each bolt 88 to space the bank 79 properly from the frame member 21 so that the contact annulus 74 is spaced from frame member 21.

Adjacent each end of the arcuate member 86 there is also an inwardly extending insulating lug 90, 91 which extends radially toward the insulating disc 70 and is of sufficient thickness to have a sliding fit between the annular members 73 and 74 at the edge 78 of disc 70. It is these lugs 90, 91 which guide the annular members 73 and 74 of the rotatable switch member 70 and hold this switch member on the shaft 35. A third such lug 92 projects radially inward from the arcuate portion 86 between the annular contacts 73 and 74.

The annular member 73 serves as a continuous contact for engaging the fixed contact member 85 and the fixed contact member 85 is located closer to the axis of the shaft 35 so that it will be in engagement with the annulus 73. The other fixed contact 80-84 are located at a greater radius so that they are out of contact with the annulus 73 but are positioned to engage a radially extending contact portion 93 which is carried by the annulus 73.

All of the contacts 80-85 may be identical in

construction and these preferably comprise resilient sheet metal members which are bent back upon themselves at the connector portion 94 which is provided with a T-shaped formation and with an aperture 95 for receiving a connecting wire. At an intermediate point each connector is secured to the arcuate insulating plate 86 (Fig. 11) by a tubular rivet 96 which passes through both the insulating plate and the contact member.

From the tubular rivet 96 each contact extends radially inward. One is bent upward at 97 and the other is bent downward at 98 to give these contact portions a spread. Then the contact portions are bent until they extend into engagement with each other at the end portions 99, 100 and each of the corners 101 is bent outward so that the two legs of each contact engage each other but the corners have a spread for the purpose of guiding the contact member 93 carried by annulus 73 between them. This spread of the fixed contact portions assures the contact 93 entering between them and wiping across both of the legs of each fixed contact.

Referring now to Figs. 1 and 2, here the panel 28 is provided with a plurality of apertures 102, each aperture consisting of an elongated portion for exposing the knurled edge 55 of the actuating disc 36 and each aperture also including a small rectangular portion for exposing an indicating numeral on the hub 54. The threaded bores 26 in frame member 21 serve to receive the screw bolts 27 which secure the switch units to the rear side of the panel with nothing but the edge of the actuating disc and the indicating numerals exposed on the front side of the panel.

All of the upwardly projecting end portions of the leaf springs 49 are located in alignment and these are adapted to be engaged by metal discs 103-105 (Fig. 1) carried by a reciprocating actuating rod 106. The rod 106 is guided by being slidably mounted in cylindrical apertures in the angle brackets 107-109 which are secured to the panel 28 by screw bolts and the discs 103-105 are located on the left side of each leaf spring 49 having reference to Fig. 3.

A helical compression spring 110 is interposed between the bracket 108 and a washer 111 on the rod 106, the washer being in engagement with a transverse pin 112. The coil spring 110 urges the rod 106 toward the left and urges the discs 103-105 out of engagement with the leaf springs 49.

A bracket 113 carried by panel 28 has a bell crank 114 pivotally mounted by a rivet 115 with one arm 116 in position to engage the end of rod 106. A push button 117 is slidably mounted in a threaded plug 118 carried by panel 28 and is confined against outward movement by a transverse pin 119. A plunger rod 120 of the push button 117 is located to engage the other arm 121 of the bell crank but a coil spring 122 urges the push button outward into the position of Fig. 1. In some embodiments of the invention this spring may be eliminated as the spring 110 on the rod 106 may accomplish the same purpose.

The operation of the switch units and of the bank of switch units is as follows: Contact 85 is the common contact which is connected to a common lead that is intended to be controlled by the switch and connected to any one of the other contacts 80-84 selectively. When the switch is in the position in which contact 93 engages contact 85, it is on open circuit with respect to the other contacts 80-84.

If the finger is then applied to the knurled edge 55 of the rotatable actuating member 36, this will tend to cause this member to rotate and the steel ball 47 will be cammed out of its first socket 46 and will ride up over the metal member 37 against the tension of the leaf spring 49 which holds the ball in the aperture 48. As the rotatable member 36 moves on farther, the ball will drop into the socket 45 and will tend to hold the rotatable member 36 in this position. In this position the movable contact member 93 engages the contact 84 having been inserted between the portions 99 and 100 of that movable contact as shown in Fig. 11.

The resistance toward movement of a ball out of its socket is such that the spiral spring 57 in the housing 54 of rotatable member 36 cannot overcome the resistance to movement of the ball and the switch is held in this position. However, each time the switch is moved a step farther away from the contact 85, the spiral spring 57 is wound up.

The rotatable member 36 may be successively brought into a position in which the steel ball 47 is retained in sockets 44, 43, 42, and finally 41, during which the contact member 93 will successively engage fixed contacts 83, 82, 81 and finally 80 and the movable switch member 70 will be retained in any of these positions by the steel ball 47 engaging in its socket.

If the operator wishes, he may move the switch backward to any desired position and at any time the position of the switch will be indicated by the numeral which is exposed at the aperture 102.

There are some uses of these switch units in which it is desirable to clear the machine or tester and move all the switches back to the initial position. In such case the arrangement of Figs. 1 and 2 is of great advantage as it is only necessary to push the push button 117 to clear all the switches. This action is as follows:

Push button 117 rotates the bell crank 114 clockwise in Fig. 1. Bell crank 114 moves rod 106 toward the right against spring 110. Discs 103-105 engage the leaf springs 49 of the respective switch units 20, permitting the steel balls 47 in each unit to be cammed out of whichever socket 41-46 the ball happens to be in. Under these conditions the steel ball 47 no longer holds the rotatable actuating member 36 in a fixed position and the spiral spring 57 in the housing 54 acts to return the rotatable switch member 70 to its initial position where the movable contact 93 engages the fixed contact 85. Thus a mere push on the push button 117 releases all of the switches to return to their initial position. In a tube tester this is of marked advantage because otherwise it would require separate manipulation of each switch unit by the operator.

The present switches maintain their contacts in a bright and low contact resistance condition and they are adapted to be moved to any one of a plurality of positions with a minimum amount of effort. The present switch may be provided with any number of banks of contacts for simultaneous or successive operation and any number of units may be mounted on a single panel to be released and returned to initial position by merely actuating one push button.

The present devices are capable of being manufactured very economically and they utilize a minimum number of separate parts. They may be used for a long period of time without necessity for repair or replacement of any of their parts and may be manufactured so economically

that they may be placed within the price range of a vast number of users.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. A rotatable switch member comprising a supporting member having a slot, a supporting frame carried by said member and having bearings for a shaft, a rotatable insulating member projecting from said slot for engagement by the fingers of an operator, an annular contact carried by said rotatable shaft and a plurality of fixed contacts carried by said frame and insulated from each other, and a snap retaining means for holding the rotatable insulating member in any of a plurality of different positions, said snap retaining means comprising a ball resiliently mounted on said frame and adapted to be engaged in any one of a plurality of sockets located in said rotatable insulating member, said ball being movable mounted in a bore in said frame and having resilient means urging it toward said sockets.

2. A rotatable switch member comprising a supporting member having a slot, a supporting frame carried by said member and having bearings for a shaft, a rotatable insulating member projecting from said slot for engagement by the fingers of an operator, an annular contact carried by said rotatable shaft and a plurality of fixed contacts carried by said frame and insulated from each other, and a snap retaining means for holding the rotatable insulating member in any of a plurality of different positions, said snap retaining means comprising a ball resiliently mounted on said frame and adapted to be engaged in any one of a plurality of sockets located in said rotatable insulating member, said ball being movable mounted in a bore in said frame and having resilient means urging it toward said sockets, said resilient means comprising a leaf spring having a projecting portion to be engaged for releasing the retaining action of said ball.

3. A snap mechanism for retaining a rotatable switch member in any position to which it is moved comprising a supporting frame, an insulating member rotatably mounted in said frame and being provided in one of its ends with a plurality of sockets arranged in a circle, said frame having an aperture adapted to register with any of said sockets, a retaining ball in said aperture and adapted to engage in said sockets and a leaf spring engaging said ball and carried by said frame and projecting beyond the end of said frame for manipulation to release the ball.

4. A snap mechanism for retaining a rotatable switch member in any position to which it is moved comprising a supporting frame, an insulating member rotatably mounted in said frame and being provided in one of its ends with a plurality of sockets arranged in a circle, said frame having an aperture adapted to register with any of said sockets, a retaining ball in said aperture and adapted to engage in said sockets and a leaf spring engaging said ball and carried by said frame and projecting beyond the end of said frame for manipulation to release the ball, said

sockets being formed in a metal plate embedded in said insulating member.

5. A snap mechanism for retaining a rotatable switch member in any position to which it is moved comprising a supporting frame, an insulating member rotatably mounted in said frame and being provided in one of its ends with a plurality of sockets arranged in a circle, said frame having an aperture adapted to register with any of said sockets, a retaining ball in said aperture and adapted to engage in said sockets and a leaf spring engaging said ball and carried by said frame and projecting beyond the end of said frame for manipulation to release the ball, said sockets being formed in a metal plate embedded in said insulating member, and said metal plate being formed with an arcuate slot for receiving a lug carried by said frame, said lug and slot serving as stops to determine the limits of rotative movement of said insulating member.

6. A snap mechanism for retaining a rotatable switch member in any position to which it is moved comprising a supporting frame, an insulating member rotatably mounted in said frame and being provided in one of its ends with a plurality of sockets arranged in a circle, said frame having an aperture adapted to register with any of said sockets, a retaining ball in said aperture and adapted to engage in said sockets and a leaf spring engaging said ball and carried by said frame and projecting beyond the end of said frame for manipulation to release the ball, said insulating member having an axially extending hub and an axially extending cylindrical housing and a spiral spring tensioned between said insulating member and said frame and located in said housing to return said insulating member to initial position when said ball is released from pressure by said leaf spring.

7. A switch assembly comprising a plurality of switch units carried by a panel, each switch unit having a disc, the edge of which projects through a slot in said panel and each switch unit being provided with a plurality of sockets in said disc engaged by a spring pressed ball carried by the switch unit frame, spring means for returning each switch unit to its initial position, movable contact means actuated by each rotatable disc and fixed contacts carried by each switch unit, a reciprocating plunger rod carried by said panel and having discs for engaging a leaf spring carried by each switch unit for urging the ball of each switch unit into its sockets, and manual means for actuating said plunger to relieve all of the balls of the switch units from spring pressure and to permit the first-mentioned springs to return each switch unit to its initial position.

8. In an electric switch unit, the combination of a supporting frame having a pair of fixed frame members provided with bearings for a shaft, a shaft in said bearings and projecting beyond said frame, said shaft having a non-circular formation at its projecting end, a rotatable insulating member of disc shape carried by said shaft for actuating the shaft, an insulating supporting plate carried by said frame adjacent the projecting end of said shaft and having a plurality of fixed contacts, an insulating disc carried by the projecting end of said shaft and rotatable with said shaft, a pair of annular metal members carried by said latter disc and projecting edge-wise therefrom to form a groove and a pair of insulating lugs projecting from said insulating plate into said groove to hold said latter insulating disc on the projecting portion of said shaft.

9. In an electric switch unit, the combination of a supporting frame having a pair of fixed frame members provided with bearings for a shaft, a shaft in said bearings and projecting beyond said frame, said shaft having a non-circular formation at its projecting end, a rotatable insulating member of disc shape carried by said shaft for actuating the shaft, an insulating supporting plate carried by said frame adjacent the projecting end of said shaft and having a plurality of fixed contacts, an insulating disc carried by the projecting end of said shaft and rotatable with said shaft, a pair of annular metal members carried by said latter disc and projecting edge-wise therefrom to form a groove and a pair of insulating lugs projecting from said insulating plate into said groove to hold said latter insulating disc on the projecting portion of said shaft, one of said fixed contacts engaging the annular portion of one of said annular metal members, and the other of said fixed contacts being located farther outward radially to engage a radially projecting contact member carried by said latter annular member.
10. In an electric switch unit, the combination of a supporting frame having a pair of fixed frame members provided with bearings for a shaft, a shaft in said bearings and projecting beyond said frame, said shaft having a non-circular formation at its projecting end, a rotatable insulating member of disc shape carried by said shaft for actuating the shaft, an insulating supporting plate carried by said frame adjacent the projecting end of said shaft and having a plurality of fixed contacts, an insulating disc carried by the projecting end of said shaft and rotatable with said shaft, a pair of annular metal members carried by said latter disc and projecting edge-wise therefrom to form a groove and a pair of insulating lugs projecting from said insulating plate into said groove to hold said latter insulating disc on the projecting portion of said shaft, said insulating disc carried by said shaft being provided with a plurality of circular sockets in one of its faces and a spring pressed ball carried by said frame for engaging in any one of said sockets to resiliently resist rotative movement of said latter insulating disc.
11. In an electric switch unit, the combination of a supporting frame having a pair of fixed frame members provided with bearings for a shaft, a shaft in said bearings and projecting beyond said frame, said shaft having a non-circular formation at its projecting end, a rotatable insulating member of disc shape carried by said shaft for actuating the shaft, an insulating supporting plate carried by said frame adjacent the projecting end of said shaft and having a plurality of fixed contacts, an insulating disc carried by the projecting end of said shaft and rotatable with said shaft, a pair of annular metal members carried by said latter disc and projecting edge-wise therefrom to form a groove and a pair of insulating lugs projecting from said insulating plate into said groove to hold said latter insulating disc on the projecting portion of said shaft, said insulating disc carried by said shaft being provided with a plurality of circular sockets in one of its faces and a spring pressed ball carried by said frame for engaging in any one of said sockets to resiliently resist rotative movement of said latter insulating disc, said spring pressed ball being engaged by a leaf spring carried by said frame and projecting beyond said frame for manipulation to release the pressure on said ball.
